UNITED STATES PATENT OFFICE

166,696

CARD GAME TRAY

Elmer H. Noelting, Evansville, Ind.

Application October 19, 1949, Serial No. 5,581

Term of patent 14 years

(Cl. D34—13)

To all whom it may concern:

Be it known that I, Elmer H. Noelting, a citizen of the United States and a resident of Evansville, county of Vanderburgh, and State of Indiana, have invented a new, original, and ornamental Design for a Card Game Tray, of which the following is a specification, reference being had to the accompanying drawing, forming part thereof.

In the drawing Fig. 1 is a perspective view of a card game tray showing my new design. Fig. 2 is a side elevation of the said tray.

I claim:

The ornamental design for a card game tray, as shown.

ELMER H. NOELTING.
